UNITED STATES PATENT OFFICE.

JOSEPH PATRICK, OF CRABTREE, PENNSYLVANIA.

COUPLING.

1,093,467.

Specification of Letters Patent. Patented Apr. 14, 1914.

Application filed December 1, 1913. Serial No. 803,928.

To all whom it may concern:

Be it known that I, JOSEPH PATRICK, a citizen of the United States of America, residing at Crabtree, in the county of Westmoreland and State of Pennsylvania, have invented certain new and useful Improvements in Couplers, of which the following is a specification, reference being had therein to the accompanying drawing.

10 This invention relates to couplers for mine, pit and other types of cars, and the primary object of my invention is to provide a car coupler of novel construction that permits of cars being easily and quickly uncoupled without the necessity of miner or trainman getting between the cars to uncouple the same.

Another object of this invention is to provide a car coupler having a novel link releasing device that under ordinary conditions holds a link as a coupling means between two cars, yet permitting of the cars being quickly released, particularly as the same are fed onto a tipple.

25 A further object of this invention is to provide a car coupler consisting of comparatively few parts that are inexpensive to manufacture, durable and applicable to the present type of pit cars.

30 With the above and other objects in view the invention resides in the novel construction, combination and arrangement of parts to be hereinafter specifically described and then claimed.

35 Reference will now be had to the drawing, wherein:—

Figure 1 is a plan of the coupler, Fig. 2 is a longitudinal sectional view of the same, and Fig. 3 is a cross sectional view of the 40 coupler.

In the drawing, the reference characters A and B denote portions of pit cars and the reference numerals 1 and 2 the sills of the cars A and B respectively. The cars are 45 provided with longitudinal draw bars 3 and 4, the draw bar 3 having a loop 5 at one end thereof and the draw bar 4 a pin 6. Movably mounted in the loop 5 is an oblong link

7 having a cross bar 8 connected to one end of a coiled retractile spring 9, the opposite 50 end of said spring being connected to an eye bolt 10, carried by the end wall 11 of the car A. The link 7 is adapted to swing downwardly over the pin 6, as shown in Figs. 2 and 3. Mounted upon the sill 2 of the car B 55 is a bearing plate 12 provided with straps 13 and movable in said straps is a slide bar 14 having a longitudinal slot 15. Extending upwardly through the slot is a pin 16 for limiting the movement of the slide bar 14 60 upon the bearing plate 12. The pin 16 is provided with a nut 17 coöperating with the straps 13 in preventing the bar 14 from becoming accidentally displaced. The inner end of the bar 14 is bifurcated, as at 18 to 65 provide clearance for the pin 6 and at the same time extend over the link 7. The outer end of the slide bar 14 is twisted and pivotally connected, as at 19 to the slotted portion 20 of an operating lever 21. The lower 70 end of the operating lever is pivotally connected, as at 22 to a bracket 23 carried by the side of the car B. The upper end of the lever is adapted to be engaged by a pivoted link or hold-fast device 24. By releasing the lever 21 and pulling outwardly upon the same the slide bar 14 is shifted from 75 above the link 7, and the tension of the spring 9 is sufficient, under ordinary circumstances, to elevate the link and thereby uncouple the cars. The link 7, when in an elevated position, can be easily lowered over the pin 6 and the cars coupled without any 80 danger of the fingers being caught between the sills of the cars.

85 The coupler in its entirety can be made of light and durable metal and used in connection with various types of vehicles.

One embodiment of the invention has been illustrated, but it is to be understood that the 90 structural elements are susceptible to such variations and modifications as fall within the scope of the appended claim.

What I claim is:—

In a car coupler, the combination with 95 car sills having draw bars, of a link loosely

2
connected to one of said draw bars, a coiled retractile spring connected to said link, a pin carried by the other of said draw bars and over which said link is adapted to extend, and a bifurcated slide bar adjacent to said pin and adapted to extend over said link to hold said link in engagement with said pin.

In testimony whereof I affix my signature in the presence of two witnesses.

JOSEPH X PATRICK.
